[57] **CLAIM**

The ornamental design for foot support panel, as shown and described.

DESCRIPTION

FIG. 1 is a perspective top and front view of the foot support panel showing my new design;

FIG. 2 is a top view thereof;

FIG. 3 is a side view thereof;

FIG. 4 is a front view thereof;

FIG. 5 is a bottom view thereof; and

FIG. 6 is a rear view thereof.

The side of the foot support panel not shown is a mirror image of the side shown in FIG. 3.

FIG. 1

FIG. 2

FIG. 3

FIG. 4

FIG. 5

FIG. 6
